CALCULATING MACHINE

Loring Pickering Crosman, Maplewood, N. J., assignor to Gardner Company, Orange, N. J., a corporation of Delaware

Application October 2, 1935, Serial No. 43,145

4 Claims. (Cl. 235—60)

The invention relates to calculating machines and more particularly to improvements in register control means.

An object of the invention is to provide simplified mechanism for controlling the character of operations to be performed upon the registering mechanism of a listing calculator, such as the well known Gardner machine; reference being made to Patents Nos. 1,927,878, issued September 26, 1933 to Harold P. Mixer, and 1,867,002, issued July 12, 1932 to Clyde Gardner, deceased.

Another object of the invention is the novel arrangement whereby the register control lever is placed in juxtaposition to the machine operating handle. The position of the two levers being such that the operator sets the register control lever during the same movement required of the hand in reaching for and operating the operating handle.

The invention consists in the novel construction and combination of parts, as set forth in the appended claims.

In the accompanying drawings, illustrating the invention:

Fig. 1 is a right side elevation of parts lying within the right hand framing of the machine, showing the register control mechanism in normal add position.

Fig. 2 is a vertical section through the keyboard, accumulator and printing mechanism.

Fig. 3 is a right side elevation of the register control means, the parts being in partially operated condition.

Fig. 4 is a detail view, showing certain control parts set for a subtract operation.

Fig. 5 is a similar view, with the parts set for non-add operation.

Fig. 6 is a detail view of the rear end of the switch carrying arm.

Fig. 7 is a right side elevation of a control mechanism modified to cooperate with motor operating means.

In the machine illustrated, amounts set up on the digit keyboard 215 (Fig. 2) are accumulated in the register 473, by engagement thereof with reciprocating actuating segments 610. The segments are reciprocated by movement of a rock shaft 301, operated by a suitable hand lever 1 (Fig. 1), said shaft being provided with cam means 318 for governing the movement of a spring tensioned rocker frame 616, mounted on shaft 608, frame 616 carrying a series of dogs 617 normally engaged by studs 659 of the levers 610. As shaft 301 is rotated forwardly (counterclockwise, Fig. 2) frame 616 will be rocked, and any of

the levers 610 which have been released by the depression of digit keys 215 will be allowed to rotate, under influence of their springs 683, until they are stopped by contact of the related stop bars 615, carried by the levers 610, with the stems 5 of the keys. Upon reverse rotation of shaft 301, the dogs 617 will return the operated levers 610 to normal position. This excursion of the levers 610 serves to register amounts set in the keyboard upon the register 473, either subtractively, by engagement of said register during the forward stroke, or additively, by engagement thereof during the return stroke of levers 610.

The accumulator shaft 403 is slidably mounted in slots of frame plates 410, as seen in Fig. 1, and 15 when said accumulator is set to active position, the gears 472 thereof will be brought into mesh with the racks of levers 610, against the tension of suitable springs, not shown, by a rocking cam plate 419, secured to shaft 2.

Cam plate 419 is operated to govern the engagement of register 473, for add, subtract or non-add operations, according to the position of a manually settable control lever 3, as will hereinafter be described.

Addition

Mounted upon shaft 2, is an arm 5, attached to the plate 419, through yieldable U-spring connection 4, the two arms of the spring being confined between lugs of plate 419 and also between lugs of arm 5, and a fixed abutment lying between the arms of the spring. Pivotedly mounted at 33, upon the rearward end of arm 5 is a switch cam 6, (Figs. 1, 3, 4, and 5). Switch 6 cooperates with a roller 7 secured to an arm 8, fast to reciprocating shaft 301, and is adapted to be set to one of three positions relative to said roller by means of setting lever 3 in the following manner:

A projection 9 of switch 6 extends between two spring pressed arms 10 and 11, said arms being loosely mounted in a suitable groove cut in the hub of full stroke arm 8. Arms 10 and 11 have projections, 12 and 13, respectively, engaging the lower end of a rock lever 14, pivotally mounted upon shaft 15. Rock lever 14 is normally held against a stop pin 69 by a spring 68 and has projections 31 and 38, located between projections 30 and 37 of a link 16, pivotally connected at 17 to the lower end of setting lever 3, said link being slidably supported at its forward end upon the shaft 15, as shown.

Lever 3 is normally held in central (or add) position shown in Fig. 1, by means of toggle spring 55

18, and spring latch 19, pivotally supported at 58 from the right hand framing of the machine. Switch 6 is thus held, through rocker 14 and arms 11 and 10, rocked in a counterclockwise direction, 5 against projection 20 of arm 5, the rearward cam surface 21 of said switch being positioned in the path of movement of the roller 7 of full stroke arm 8.

During the first portion of the forward movement of operating handle 1, roller 7 will engage cam surface 21 of switch 6 (forming in effect an upper extension of the rear surface of flange 22), passing under the switch, raising arm 5 about point 2, and rocking cam plate 419 counterclockwise, to the position illustrated in Fig 3. The above described movement of plate 419 brings a low point of its cam edge opposite a collar of shaft 403 and thus releases register 473, allowing said register to be disengaged from the actuator 10 racks 610 before said racks are allowed to move. Thus racks 610 will move idly during the forward stroke of lever 1, the arm 5 being held in raised position until the end of the forward stroke of said lever by means of roller 7 engaging the 15 under surface of a guide flange 22, of said arm. At the end of the forward stroke roller 7 will have passed from beneath flange 22 and will lie adjacent cam surface 23 of switch 6. During the return movement roller 7, acting upon surface 23, 20 will restore arm 5, rocking plate 419 counterclockwise to reengage registers 473 with the racks 610. The return movement of said racks will now impart counterclockwise or additive movement to the registers 473.

35

Subtraction

To set the control means for subtraction, the operator, in reaching for the operating handle 1, slides the base of the thumb across a suitable 40 knob 24 of the setting lever 3 (see Fig. 1) rocking said lever clockwise about point 25, and then, by flexing the fingers slightly, lever 1, and thus full stroke arm 8, is moved forward sufficiently to bring a locking flange 26 of said arm above 45 the surface 27 of a forward arm of latch 19, thus, by engagement of stud 28 of said latch with notch 29, of setting lever 3, locking said lever in subtractive position during the operative movement of handle 1.

50 Clockwise movement of lever 3 has moved link 16 forwardly, the projection 30 of said link engaging pin 31 of rocker 14 and imparting a clockwise movement to said rocker. Clockwise movement of rocker 14 will rock arm 10 and (through 55 spring 32) the arm 11, counterclockwise about point 301. The described movement of arm 11 will cause said arm, by engagement with projection 9, to rock switch 6 clockwise about its pivot point 33, to the position illustrated in Fig. 4, 60 wherein the surface 21 of said switch is rocked out of the path of movement of roller 7. Roller 7 thus moving idly past the switch and over guide plate 22 on the forward stroke, register 473 will remain in engagement with the racks 610 to implement clockwise or subtractive movement to the 65 registers 473.

At the end of the forward stroke roller 7, having momentarily displaced the switch and passed beyond the same, will be positioned adjacent the 70 surface 34 of switch 6 and, during return movement, will engage said surface, raising the arm 5 and rocking cam plate 419 to disengage register 473 from the rack 610 during the return movement of said racks to their normal position. The 75 roller 7 in passing beneath the flange 22 locks arm

5 and plate 419 in raised position. Near the end of the return movement of the parts, roller 7 engages a projection 35 of arm 5 to restore said arm and plate 419 to normal position. At the end of the return movement of arm 8, plate 26 releases latch 19, whereupon springs 18 and 19 will restore control lever 3 to its normal central position, spring 18 being of sufficient power to move the stud 26 out of notch 29.

Non-add

In non-add operations wherein listing is to be effected without accumulation on the register, control lever 3 will be rocked counterclockwise by the operator and locked in said position by 15 engagement of stud 28 with notch 36 in the manner described for subtractive operations. Counterclockwise movement of lever 3, however, will cause link 16 to move rearwardly, and the projection 31 of said link will contact the projection 38 20 of rocker 14, imparting a partial movement clockwise to said rocker, bringing the parts to the position illustrated in Fig. 5, wherein the switch 6 will be moved and held, by arms 10 and 11, 25 out of cooperative relation with roller 7. Roller 7 will thus move idly during a forward and return movement of the parts, the plate 419, remaining in normal position. The register 473 will thus be held in engagement with racks 610 during both the forward and return movements 30 of said racks, whereupon any values, set up on digit keys 215, will be rotated into said registers during the forward stroke, but will be rotated out during return movement of the parts.

35 Yieldable stops 39 (Fig. 1) are provided to limit the movement of the operating handle and associated parts, these stops being adapted to absorb impact and minimize noise.

Totals

40 Since, as described in the aforementioned patents, the taking of a total involves a subtractive setting of the machine, projection 54 of the total key 278 (Fig. 1) by engagement with pin 55 of rocker 14 is adapted to give said rocker its full 45 clockwise movement, to set the parts for a subtractive operation, in the manner previously described. In taking a sub-total, values stored upon registers 473 are to be retained, wherefore said registers are left in engagement with the actuating segments 610 during the forward and return strokes thereof. Upon operation, the sub-total key 273, therefore, is adapted by engagement of its projection 56 with projection 57 of pawl 14, 50 to give said pawl a partial step of clockwise movement and thereby set the control mechanism in the position described with relation to the non-add operation.

Power operation

60 Power means may be provided for operating the machine, in accordance with the disclosure of Patent No. 1,932,013, issued on October 24, 1933 to Loring P. Crosman. This means, as illustrated in Fig. 7, comprises a motor 100 having drive connection with notched disc 157 and adapted to operate in the following manner:

Upon depression, operating key 138, fulcrumed upon the framing at 139, will rock latch 147 to disengage hook end 148 from lever 150.

70 Disengagement of hook 148 from lever 150 will allow said lever, under influence of spring 151, to be rocked out of engagement with the projection 152 of a clutch pawl 153, pivotally mounted upon the crank arm 155, allowing said pawl, under in-

fluence of its spring 156, to be rocked into engagement with notched disc 157.

During the above described movement of lever 158, an insulated roller 63, fast thereto, will effect contact of the points 64 of motor switch 65, to start the motor and rotate notched disc 157.

During an operating cycle of the machine crank arm 155, having link connection 161 with an arm 316, fast to shaft 301, will impart reciprocating movement to said shaft, to provide for register operation in the manner previously described.

Toward the end of the cycle of operation an arm 158 of crank 155 will contact with a tooth 159 of the lever 150 and will force said lever back into latching position, breaking the electric circuit and bringing the end of lever 150 into the path of movement of projection 152 of pawl 153 to disengage said pawl from driving disc 157 and check further rotation of the parts.

A control lever 58, similar to the lever 3, is arranged in juxtaposition to key 138, in such manner as to be movable by the thumb of the operator as key 138 is depressed by the base of the thumb.

Lever 58 controls the character of operation to be performed upon register 403 in the same manner as described for the lever 3.

The following means will prevent a machine cycle if lever 58 should be but partially operated when key 138 is depressed:

Stud 59, secured to lever 150 and upon which the insulated roller 63 is mounted, extends through a suitable aperture provided in a lever 60. Lever 60 is fulcrumed at 61 and is provided at its upward end with a projection 62.

Release of lever 150, upon depression of key 138 as previously described, will cause said lever through stud 59 to rock lever 60 counterclockwise, bringing projection 62 into engagement with the notch 71 of lever 58 and thereby preventing operation of said lever during an operating cycle of the machine.

If however lever 58 is operated simultaneously with key 138, notch 71 will have been rocked out of the path of movement of projection 62 and said projection will contact the surface 66, to prevent further movement of lever 150 until lever 58 has been fully operated thereby releasing projection 62 from surface 66.

Suitable projections 67 of surface 66 will prevent lever 58, if partially operated, from returning to normal under influence of spring 18, insuring that said lever must be correctly positioned before the machine can operate.

I claim:

1. In a calculating machine having means selectively settable to control plus or minus registration, and motor drive means therefor including a normally restrained drive initiating member and a key manipulable to release said member; a manually adjustable setting lever for said first named means, and interlock means between the motor drive and the setting lever, including means operable upon incomplete adjustment of the setting lever to hold the released drive initiating member inactive.

2. In a calculating machine having a register and reciprocable register actuators; means selectively settable to control actuation of said register by said actuators upon movement thereof in a given direction, including a member reciprocable with said actuators and provided with a roller, a lever adjustable to control the registration and provided with a guide flange cooperating with said roller, and an adjustable switch pivotally mounted upon said lever and cooperating with the roller to rock the lever and shift the flange across the path of movement of said roller.

3. In a calculating machine having a register and reciprocable register actuators; means selectively settable to control actuation of said register by said actuators upon movement thereof in a given direction, including a member reciprocable with said actuators and provided with a roller, a lever adjustable to control the registration and provided with a guide flange cooperating with said roller, an adjustable switch pivotally mounted upon said lever and cooperating with the roller to rock the lever and shift the flange across the path of movement of said roller and a pair of opposed spring arms adapted to locate the switch in an intermediate adjusted position.

4. In a calculating machine having a register and reciprocable register actuators; means selectively settable to control actuation of said register by said actuators upon movement thereof in a given direction, including a member reciprocable with said actuators and provided with a roller, a lever adjustable to control the registration and provided with a guide flange cooperating with said roller, an adjustable switch pivotally mounted upon said lever and cooperating with the roller to rock the lever and shift the flange across the path of movement of said roller, a pair of opposed spring arms adapted to locate the switch in an intermediate adjusted position, and a three position rocker controlling said spring arms.

LORING PICKERING CROSMAN.
